APPARATUS FOR DESCRIBING AND
TRACING CURVES

Elia Africano, Turin, Italy

Application August 4, 1934, Serial No. 738,547
In Italy August 11, 1933

7 Claims. (Cl. 33—27)

The present invention relates to an apparatus for describing and tracing curves such as an ellipse, a sine curve, cycloids, an Archimedean spiral, etc., characterized by two pairs of cranks, the parallel axes of rotation of which are arranged in pairs in two planes perpendicular to each other and are connected to a supporting frame while means are provided for maintaining the cranks parallel during their rotation and it is further characterized by two rods each pivoted to the cranks of a pair, at points situated at a predetermined distance from the axis of rotation of these same cranks. The point of intersection of the said rods being materialized by an intersection member sliding upon the two rods, each point on the said intersection member describing curves identical to those described by the point of intersection of the two rods so that a tracing point or an operative tool secured to the said intersection member will serve for tracing or materializing these same curves on a piece of work.

One embodiment of the subject of the invention is illustrated simply by way of example and diagrammatically in the accompanying drawings in which:—

Figure 1 illustrates the method for the geometrical construction of an ellipse followed by the apparatus according to the present invention.

Figure 2 shows diagrammatically in plan view the apparatus employed as an ellipsograph.

Figure 3 shows in detail the member applied to correspond with the point of intersection of the two rods.

Figure 4 shows one of the cranks in detail in plan view and in vertical longitudinal section.

Figure 5 shows diagrammatically in plan view the apparatus employed for tracing sine curves.

Figure 6 shows in detail in plan view and in vertical longitudinal section a modification of the crank made in order to adapt the apparatus for describing an Archimedean spiral.

Figure 7 is a plan view showing the apparatus fitted with a dividing device.

The apparatus will first be described in its application to an ellipsograph.

It is known that an ellipsograph can be constructed geometrically (see Figure 1) by tracing, with a common centre o , two circles of radius a and b equal to the two half axes of the ellipse to be constructed, by then tracing any radius ρ which intersects circles a and b at M and N respectively and by finally tracing the intersection P of the straight lines A, A , and B, B , which pro-

ject the points M and N respectively upon the two perpendicular axes x and y passing through o .

This point P is a point on the desired ellipse. In fact if ϕ is the angle formed by the radius ρ with the axis x we have: $x=a \cos \phi$ and $y=b \sin \phi$ which is in fact the parametric equation of the ellipse having half axes a and b .

Now the apparatus according to the present invention reproduces mechanically precisely the geometric construction of the ellipse described above.

This apparatus comprises (see Figure 2) two pairs of cranks $1, 1$, and $2, 2$, the axes of rotation $1', 2'$, of which are parallel and are arranged in pairs in two planes at right angles to each other and which when projected in plan give the perpendicular axes x and y intersecting at o .

The axes of rotation of the cranks are supported in a fixed position by a frame formed for example by a supporting plate 3. With the object of preserving the parallel relation between the various cranks during their rotation, each axis of rotation of these cranks is provided with a toothed pinion $1''$ and $2''$ respectively and all these pinions which are identical with one another engage in a toothed crown 4, supported so as to be capable of turning by the plate or arm 3. The plates $1, 1$ and $2, 2$, of each pair are provided with crank pins $1a, 1a$ and $2b, 2b$ respectively, which are adjustable in position in a radial direction and to which are pivoted respectively the crossed rods 5 and 6.

The crank pins $1a, 1a$ are situated at the same distance from the axis of rotation $1'$ of the corresponding crank 1 . In a similar manner the crank pins $2b, 2b$ are situated at the same distance from the axis of rotation $2'$ of the corresponding crank 2 .

Upon the crossed rods $5, 6$, which must naturally be arranged in two distinct planes, so that one will not impede the movements of the other, is mounted at the point of intersection a member 7, adapted to slide on both rods 5 and 6 at the same time.

From the constructional point of view the cranks $1, 2$, have the form of forks as will be seen in Figure 4, which illustrates one of the cranks 2 .

Between the two arms of the fork is arranged a screw 8, mounted so that it can turn by means of its end pivots $8', 8''$ in the end of the fork and in a cross member 9, which serves to close the end of the fork. The rod 10 of the crank pin $2b$ to which the rod 6 is pivoted engages with the screw 8, which can be rotated by means of the end knob $8a$, so that this pin can thus move radially.

along the crank in order to place it at a predetermined distance from the axis of rotation of this same crank or if desired in order to make it coincide with this axis.

5 A scale 11 is engraved upon one of the arms of the crank, and a pointer 12 rigid with the pin enables the position of the crank pin with respect to the axis of the crank to be established accurately.

10 The crank 2 bearing by its flange 13 upon the supporting plate 3 is mounted so that it can turn with its pivot 2' in a suitable hole in the plate itself, while below the latter upon an extension of the pivot 2' is keyed the pinion 2'' adapted to engage with the toothed crown 4.

15 The intersection member 7 slidably mounted upon the two rods 5, 6, is preferably formed by a sleeve having a closed end (see Figure 3) in the peripheral wall of which are formed at different heights two pairs of holes through which the said rods pass.

20 The method of use and of operation of the apparatus described above is as follows:—

25 It is assumed that the crank pins 1a, 1a, of the cranks 1 have been moved to a distance a from the axis of rotation of these cranks and the pins 2b, 2b of the cranks 2 to a distance b from the axis of rotation 2' of the corresponding cranks.

30 When the four cranks turn while preserving their parallel relation the rods 5 and 6 which reproduce straight lines A, A, and B, B, in Figure 1, move while always remaining parallel to their original direction and each point on these rods describes a circle of radius a and b respectively. 35 The point of intersection P of these rods consequently describes an ellipse e , having half axes a and b . Each point on the intersection member 7 which while moving along the rods 5 and 6 preserves an unvarying position with respect to the point P consequently describes the desired ellipse. Consequently if an arm provided with a tracing point is rigidly secured to the screw threaded pivot 7' of this member 7, this point will 40 trace the desired ellipse on the plane of the drawing. If instead of a point the said arm is connected to a working tool such as a milling cutter, this tool can be employed for reproducing the desired ellipse on a piece of work.

45 By changing the radii a , b of the cranks various ellipses can be obtained. By making a to b , the apparatus will trace a circle of radius $r=a=b$. If a is given any value and if $b=0$, that is to say if the pins 2b are made to coincide with the axis of rotation 2' of the cranks 2 (Figure 5) and further if the whole apparatus is given a movement of translation in the direction of the axis y in such a manner that this assembly travels over spaces proportional to the angle of rotation ϕ of the cranks it is obvious that the tracing point secured to the intersection member 7 will trace a curve of equation $x=a \sin \phi$ that is to say a sine curve.

50 In order to obtain such a movement of translation of the apparatus for example it may be guided by a slide block 3' rigid with the plate 3 along a fixed guide 14 parallel to the axis y while the pinion 2'' of one of the cranks 2 or any other pinion of suitable diameter keyed upon the same axis of rotation 2' is brought into engagement with a rack 14' rigid with the guide 14 or cut directly in this same guide.

55 By varying a the amplitude of the sine curve is varied. By varying the diameter of the pinion which engages in the rack 14', the periodicity of the sine curve is varied.

By displacing the whole of the apparatus in the direction of the axis y sine curves may be traced which are displaced relatively to each other by any quantities.

60 The translational movement of the whole of the apparatus instead of being obtained by means of a rack 14' and a pinion rigid with the pivot 2' may be obtained by means of a cable wound in one of the grooves of a cone of grooved pulleys keyed upon the pivot 2', the said cable being held in tension at its ends and arranged parallel to the axis y .

65 If in the apparatus mounted, as in Figure 5, the pins 2b of the cranks 2 are moved to the same distance from the pivot 2' as the pins 1a are from 1', that is to say if a is made equal to b , it is then possible to trace cycloids in which the radius of the rolling circles is $r=a=b$. If $a=b > r$ elongated cycloids are traced; if $a=b < r$ shortened cycloids are traced.

70 Finally if $a \neq b \neq r$ an infinite variety of curves can be traced, the general equation of which referred to the axes is $x=a-a \cos \phi$, $y=r \phi-b \sin \phi$.

75 The apparatus can also serve for describing an Archimedean spiral, the equation of which is $r=c \phi$ where c is a constant.

80 For this purpose, the radius of all the cranks must change proportionally to the angle of rotation ϕ . In order to satisfy this condition, the cranks may be given the modified shape shown in Figure 6, in which a bevelled pinion 15 is keyed upon the screw 8, and engages with another bevelled pinion 16 which is fixed and coaxial with the axis of rotation of the crank.

85 During the rotation of the cranks, the corresponding pinion 15 by meshing with the fixed pinion 16 will turn and rotate the screw 8, so that the corresponding crank pin will move proportionally to the angle of rotation of the cranks.

90 The tracing point secured to the intersection member 7 will consequently trace an Archimedean spiral. During this operation the base plate 3 must be maintained in a fixed position as is obvious.

95 The apparatus may advantageously be provided with a dividing device as shown in Figure 7.

This dividing device comprises an extension 17, adapted to bear upon the plane of the drawing and to which the base plate 3 of the apparatus is removably connected in any suitable manner. The pinion 2'' of one of the cranks engages in an equal pinion 18, keyed upon the vertical shaft 19, carried by the extension 17, and provided with a bevelled pinion 20, engaging in an equal bevelled pinion 21 keyed upon the shaft of a dividing drum 22.

99 The surface of the drum upon a plurality of generating lines is provided with a number of various graduations 22', 22'', etc., which subdivide the corresponding generating lines into a certain number of equal parts.

104 Each of these graduations can be read through a slot 23' opposite reference pointer 23'' on a slide block 23 movable in an axial direction and provided with another reference pointer 23''' adapted to be brought into register with the graduations of a fixed scale 24 with the object of indicating the number of sub-divisions of the 109 graduations actually visible through the slot 23'.

110 When tracing an ellipse the drum 22 turns and the sub-divisions of the chosen graduation pass successively opposite the pointer 23'' so that

it is possible to mark on the curve being traced the corresponding sub-divisions.

It is obvious that from the constructional point of view the apparatus may undergo numerous modifications and that the invention is in no way limited to the diagrammatic forms above illustrated and described.

Having now described my invention, what I claim as new and desire to secure by Letters Patent is:—

1. In an apparatus for describing and tracing sine curves, cycloids and other curves, the combination with an ellipsograph of the type comprising a supporting frame, two pairs of parallel cranks rotating on two pairs of pivots fixed to the supporting frame and arranged in two axial planes perpendicular with each other, each of the cranks including an adjustable crank pin, two crossed rods each pivoted to the adjustable crank pins of a pair of cranks, and a sliding member bearing the tracing tool mounted in the point of intersection of the said rods, of guiding means associated with the ellipsograph whereby the apparatus can be given a movement of translation in the direction of one of its axes and whereby its movement of translation can be controlled proportionally to the rotation of the cranks in order to trace sine curves or cycloids.

2. An apparatus according to claim 1, characterized by the feature that the whole of the ellipsograph by means of a slide block rigid with its supporting frame is mounted capable of being displaced in the direction of one of its axes along a fixed guide, while the translation is obtained by means of a pinion rigid with one of the cranks of the ellipsograph and in engagement with a rack rigid with the said fixed guide.

3. An apparatus according to claim 1, characterized by the feature that a pinion is keyed upon

the axes of each crank of the ellipsograph, the said pinion engaging with a toothed crown rotatably supported by the supporting frame of the ellipsograph, whereby the parallel relation between the cranks is maintained during their rotation.

5

4. An apparatus according to claim 1, characterized by the feature that the pin of each crank engages with a longitudinal screw arranged between the two arms of the fork shaped crank and adapted to be rotated so as to displace the said pin with respect to the axis of rotation of the crank.

10

5. An apparatus according to claim 1, characterized by the feature that the pin of each crank engages with a longitudinal screw arranged between the two arms of the fork shaped crank and adapted to be rotated so as to displace the said pin with respect to the axis of rotation of the crank, the said longitudinal screw of each crank being provided with means adapted to rotate the said screw during the rotation of the crank itself, whereby an automatic displacement of the crank pin can be obtained.

15

6. An apparatus according to claim 1, having a sliding member bearing the tracing tool mounted in the point of intersection of the two crossed rods of the ellipsograph, characterized by the feature that the said sliding member is provided with a screw threaded pivot on which an arm bearing the tracing tool is secured following any desired direction.

20

7. An apparatus according to claim 1, further comprising a separated dividing drum for effecting a corresponding sub-division of the curve being traced, and a transmission device between said drum and one of the cranks of the ellipsograph to control the drum.
